METHOD OF MECHANICALLY PRODUCING A BUNCH-SHAPED HOLLOW RIB IN THE BACK PLATE OF ARTIFICIAL TEETH

Application filed October 4, 1930, Serial No. 486,297, and in Germany December 6, 1928.

The present invention relates to a method of producing back-plates for artificial teeth. The back-plates consist of a plate of metal with a rib being reinforced by a head at its edge. The back parts of the bodies of the teeth possess a plane face and a notch in this face corresponding exactly to the cross-section of the rib, so that they may be shifted. The bunch pressed out of the plane of the rib of the plate in the longitudinal direction of the rib and secured thereon, whilst its plane back supports to the plane final shape is formed according to Fig. 2. With a sufficient degree of ability it is possible to accommodate the form of the rib to the form of the notch of the body of tooth to be put up by pressing the rib more or less out of the plane of the plate and by pressing together more or less the two walls of the rib. According to another method of manufacture the plate is rolled together with the rib. In this manner the final back plate may be produced as a profiled bar, from which then the single back plates are cut off. One part of the bar must be severed still from the plate itself. These bars are very solid indeed, but because the artificial teeth are of very different size, it is necessary to keep a good stock of such bars in hand, or to work a uniformly manufactured plate so that it is adjusted to the teeth in question. Because the back plates are made in the most cases of gold of high value, the keeping of such a stock is involved with large expenses. Furthermore this method gives many chips which may be recovered only by melting down.

It has also already become known to manufacture back plates for teeth by the aid of flat nose pliers, having a mouth the width of which is equal to the height of the plate to be made and having transversely to the mouth on the one side a rib and on the other side a notch. By the use of such flat nose pliers it is, however, only possible to produce a bunch in the plate to be worked extending over the whole height of the plate. This bunch is then pressed together from the sides so that a round rib is formed. This procedure has the disadvantage that afterwards a portion of the rib must be removed again, so that a slot is formed in the plate which must be closed again by soldering.

These disadvantages shall be obviated by

the method according to the invention and represented in the annexed drawings. The method consists in that at first a bunch with a length corresponding to the bar to be produced is pressed from the plane plate, as shown in Fig. 1, keeping during this time the other portion of the plate under flat pressure of the rib, so that they may be shifted. The bunch pressed out of the plane of the plate will then be pressed together in the direction of the rib and secured thereon, known manner from the sides, so that the final shape is formed according to Fig. 2. With a sufficient degree of ability it is possible to accommodate the form of the rib to the form of the notch of the body of tooth to be put up by pressing the rib more or less out of the plane of the plate and by pressing together more or less the two walls of the rib. According to another method of manufacture the plate is rolled together with the rib. In this manner the final back plate may be produced in short time separately for each tooth to be inserted, so that the keeping of an expensive stock is not necessary. If sheets of small thickness, for instance to 0.3 mm. are used, it is preferable to insert a correspondingly thick core of steel or gold wire before pressing laterally together the U-shaped rib in such a manner that the bunch surrounds and holds fast the wire after the pressing process.

For accomplishing this method preferably flat nose pliers as shown in Fig. 3 are used. The rib *a* arranged on one side of the mouth fits together with the free play dependent from the thickness of the sheet of metal into the notch *b* of the other part of the mouth, so that if the flat nose pliers will be closed a U-shaped rib is pressed out from the sheet of metal in the mouth of the flat nose pliers, as shown in Fig. 1. At a certain distance from one or both of the outer edges the flat nose pliers are provided with notches *i*. If the plate formed according to Fig. 1 is laid laterally into the mouth of the pliers and these are pressed together, the edges *c* press firmly together the rib, whilst within the groove formed by the notches *i* the bunch-shaped head of the rib is formed (Fig. 2).

In practice it has been found that the flat main portion of the plate shown in Figure 1, when the U-shaped rib is compressed to form

the tubular head as shown in Figure 2, will not be disfigured or bent at all or to a very slight degree only. In case of such a slight disfiguration of the plate, however a light pressure or tapping on the plate while still firmly held between the plier jaws will be sufficient to remedy the defect and remove the bend or bulge. The metallic material of which the plate is made is so ductile as to not only withstand the comparatively vigorous dilatation at the closed end of the rib due to the bulging operation or effect, but also prevents bulging or bending of the plate near the closed end of the rib at the subsequent operation of forming the tubular head.

What I claim is:—

1. Method for mechanically producing a bunch-shaped hollow rib in the back plates for artificial teeth with a corresponding notch 20 on their back part consisting in pressing out from a plane sheet of metal a hollow rib extending in the longitudinal direction of the said metal sheet but only over a part of the length of the back plate, whilst the other part 25 protruding over said rib is kept under flat pressure, whereupon both side-walls of the rib are pressed together in known manner so that the cross section of the head of the rib has more or less the form of an approxi- 30 mately closed circle.
2. Flat-nose pliers for accomplishing the said process with a rib on one plier and a corresponding notch in the other plier, said rib and notch extending only over a portion 35 of said pliers and leaving free the other portion of the same, serving for exerting during the pressing operation a flat pressure on that portion of the back-plate to be worked which extends over the hollow rib, produced in said 40 plate.

In testimony whereof I have signed my name to this specification.
